BUTTONHOLE SEWING MACHINE

Franklin A. Reece, Brookline, Mass., assignor to
The Reece Button Hole Machine Company,
Boston, Mass., a corporation of Maine

Application October 16, 1931, Serial No. 569,135

14 Claims. (Cl. 112—158)

This invention relates to buttonhole sewing machines and particularly to the mechanism for giving the needle its lateral jogging movement to cause it to penetrate the work alternately at the buttonhole slit and at a distance back from the slit. For convenience the thrusts of the needle through the goods at the buttonhole slit will be referred to as "slit" thrusts while the thrusts of the needle through the work back from the slit 5 will be referred to as "depth" thrusts.

When the sewing of the buttonhole is completed each buttonhole stitch will include a portion of thread extending from a slit thrust to a depth thrust. The length of these portions of thread, 15 which is sometimes referred to as the "bight" of the buttonhole stitch, is determined by the extent of the lateral jogging movement which the needle has.

In the operation of buttonhole sewing machines 20 it is sometimes desirable to vary the bight of the buttonhole stitch, or, in other words, to vary the amplitude of the jogging movement of the needle. In some fabrics it is important to sew a buttonhole with a wide bight which would be accomplished by giving the needle an increased amplitude of jogging movement, and for other purposes it may be desirable to sew the buttonhole 25 with a narrow bight, which is accomplished by adjusting the needle-jogging mechanism so that 30 the needle will have a decreased amplitude of jogging movement. Moreover, in sewing buttonholes in some fabrics it is desirable that the slit thrusts of the needle for the stitches on both sides of the buttonhole should be in the exact center line of 35 the buttonhole while in sewing buttonholes in some other fabrics, such for instance as coarsely woven or knitted fabrics, it is desirable to so adjust the stitch-forming mechanism that the slit thrust of the needle will be spaced from the center line of the buttonhole, in which case the two 40 lines of slit thrusts formed when the two sides of the buttonhole are sewed will be spaced from each other.

In prior buttonhole sewing machines with 45 which I am familiar the means for adjusting the amplitude of jogging movement of the needle, or the bight of the stitches, is such that any change in the length of the jogging movement which is made when the needle is set for making its slit thrusts at any point other than the center line of the buttonhole involves also a change in the position of the slit thrusts of the needle and, therefore, in these prior buttonhole sewing machines 50 if it was desired to change the bight of the buttonhole stitch when the needle is set to make slit

thrusts at one side of the center line of the buttonhole without, however, changing the position of the slit thrusts of the needle it has been necessary to make two adjustments, that is, first to make the adjustment to secure the desired amplitude of jogging movement of the needle and then to make a subsequent adjustment in order to center the stitches and bring the line of slit thrusts back to the desired or initial position.

One object of the present invention is to provide a novel needle-jogging mechanism which can be adjusted to vary the amplitude of the jogging movement of the needle without, however, changing the position of the slit thrusts regardless of the position of the slit thrusts of the needle relative to the center line of the buttonhole so that if a change in the bight of the stitches is desired without any change in the position of the slit thrusts of the needle a single adjustment is all that is necessary.

Another object of the invention is to provide a novel means for adjusting the position of the needle to enable the slit thrusts to be made at any desired point transversely of the buttonhole slit, which means is independent of the means for varying the amplitude of jogging movement of the needle.

In my present invention, therefore, the two adjustments, one for varying the amplitude of jogging movement of the needle and the other for varying the position of the slit thrusts of the needle, are independent and each adjustment can be made without changing the other adjustment.

In order to give an understanding of the invention I have illustrated in the drawings a selected embodiment thereof which will now be described after which the novel features will be pointed out in the appended claims.

Fig. 1 is a side view of a portion of a buttonhole sewing machine embodying my invention;

Fig. 2 is a section on the line 2—2, Fig. 1;

Fig. 3 is a section on the line 3—3, Fig. 2;

Fig. 4 is a view taken at right angles to Fig. 3;

Figs. 5 and 6 are diagrammatic views showing the operation of varying the amplitude of jogging movement of the needle without varying the position of the slit thrusts thereof.

The buttonhole sewing machine illustrated in the drawings has the usual work-holding means 1 by which the work 2 in which the buttonhole 50 is to be sewed is clamped to the bed 3 and also the usual buttonhole cutter 90 by which the buttonhole slit is cut. The stitch-forming mechanism comprises the usual needle 4 operating from above the work and suitable under thread 55

mechanism situated beneath the work and carried by the usual rotary turret 5.

The needle is mounted in a needle bar 6 which has vertical reciprocation in the head 7 of a stitch frame 8, the latter being mounted on the bed 3. The needle bar derives its vertical reciprocation from a cam 9 mounted on a cam shaft 10, said cam having a cam path 11 which receives a follower 12 carried on the end of a lever 13 situated within the frame 8 and pivoted thereto to rock about a center 14, the outer end of the lever being suitably connected to the needle bar as shown at 15.

The needle bar also has a back and forth lateral jogging movement so that the alternate thrusts, or slit thrusts, will be along the line of the buttonhole slit while the other thrusts, or depth thrusts, will be through the fabric at a distance back from the slit. The means for thus giving the needle its jogging movement are similar in many respects to that usually employed in sewing machines of this type, an exemplification of which will be found in the Patent No. 1,437,847, December 5, 1922.

The needle bar extends through and is guided by a sleeve 16 which in turn extends axially through a gear member 17 by which the needle bar is turned in sewing around the end of the buttonhole. The axial opening 18 through the gear is larger than the sleeve 16 so as to permit the sleeve to be shifted laterally in said opening thereby to accommodate the necessary lateral jogging movement of the needle.

The sleeve 16 is provided at its lower end with two oppositely-disposed inclined grooves 19 and the gear 17 is provided with two depending ears 20, each of which carries a spring-pressed shoe 21 having a toe portion 22 which occupies one of the grooves 19.

Means are provided for reciprocating the sleeve 16 in a vertical direction, and because of the engagement of the stationary toes 22 with the grooves 19 such vertical reciprocation will cause the sleeve and the needle bar to be moved back and forth laterally thereby to produce the slit thrusts and the depth thrusts.

The sleeve 16 derives its vertical reciprocation from a cam member 23 mounted on the cam shaft 10 and having a cam groove 24 in which is received a follower 25 on a lever 26 pivoted at 27 to the frame 8. The operative connections between the lever 26 and the sleeve 16 includes a rocker member 31 which is journaled in the frame 8 and which is provided with two arms 30 and 32. The arm 30 is connected to the lever 26 through the medium of a fixed-length link 29, the latter being pivoted at one end to said lever at 34. The other arm 32 of the rocker member has a forked portion 33 which embraces the upper end of the sleeve 16 and is pivotally connected to trunnions or projections 34 extending from a collar 35 mounted on the sleeve and in which the sleeve is free to turn. The oscillating movement of the lever 26 will thus operate through the rocker 31 to reciprocate the sleeve 16 in a vertical direction with the result that the needle will be given its lateral to-and-fro jogging movement.

The position which the slit thrusts of the needle have with reference to the center line of the buttonhole depends upon the position in a vertical direction which the sleeve 16 occupies when the machine comes to rest at the completion of a buttonhole cycle or, in other words, it depends upon the initial position in a vertical direction of the sleeve 16. The machine herein shown has

suitable means, which will be presently described, for adjusting the vertical position of the sleeve 16 and thereby adjusting the position of the slit thrusts of the needle.

The cam 24 has a fixed throw and for varying the amplitude of the jogging movement the link 29 is adjustably connected to the arm 30, this being the usual practice. The arm 30 is shown as having a slot 36 in which the pivotal connection 37 between the link 29 and the arm can be adjusted, thereby to vary the amplitude of oscillation of the rocker member 31. In the present invention, however, the link 29 is of fixed length and the slot 36 has such a shape that when the machine is at rest with the needle raised, said slot will form the arc of a circle struck from the pivotal connection 34 as a center. Hence with the parts in this position the pivot point 37 may be adjusted longitudinally of the slot 36 without changing the position of the arm 30.

The shifting of the pivot point 37 toward the outer end of the slot will result in decreasing the amplitude of the jogging movement of the needle or the bight of the stitch while adjustment of the pivot pin 37 toward the lower end of the slot 36 will increase the amplitude of jogging movement of the needle or the bight of the stitch.

Since this adjustment can be made without changing the position of the arm 30 and consequently without changing the vertical position of the sleeve 16 there will be no change in the position of the slit thrusts of the needle due to the shifting of the pivot 37 in the slot 36 and hence with the construction described the amplitude of jogging movement of the needle or the bight of the stitch may be adjusted without producing any change in the position of the slit thrusts of the needle, and this is true regardless of the position in which the slit thrusts of the needle are made transversely of the buttonhole. This is illustrated in Figs. 5 and 6 wherein 38 indicates the buttonhole slit. In Fig. 5 is illustrated diagrammatically a buttonhole in which the slit thrusts of the needle are in line with the buttonhole slit, such slit thrusts being indicated at 39. In Fig. 6 is illustrated diagrammatically a buttonhole in which the slit thrusts are situated at one side of the buttonhole slit, such slit thrusts being indicated at 45.

Assuming that the sewing machine is adjusted for making wide bight stitches with the slit thrusts of the needle in the line of the buttonhole slit as shown at 39 in Fig. 5 and the depth thrusts at points indicated at 40, in which case the wide bight stitches will be indicated by the full lines Fig. 5, and it is desired to produce a buttonhole with stitches having a narrower bight but with the slit thrusts of the needle still in the line of the buttonhole slit, then the pivotal connection 37 will be adjusted toward the outer end of the slot 36, which will result in producing the narrow bight stitches indicated in dotted lines Fig. 5 wherein the depth thrusts will be at the points indicated at 42. This adjustment, however, does not affect in any way the position in which the slit thrusts will be made and they will still be in the line of the buttonhole slit as indicated in dotted lines Fig. 5. In other words, with the construction above described the change in the amplitude of the jogging movement of the needle, whether such change is an increase or a decrease, occurs entirely on one end of said movement, that is, on the depth thrust end thereof.

Similarly, if it is assumed that the sewing ma-

chine is adjusted for making a wide bight stitch but with the slit thrusts of the needle at one side of the buttonhole slit as shown in full lines Fig. 6 wherein the slit thrusts are indicated at 5 54 and the depth thrusts at 55, then the shifting of the connection 37 in the slot 36 to make the narrow bight stitches shown in dotted lines Fig. 6 will cause the thrusts of the needle to be made as shown by dotted lines Fig. 6, that is, the slit 10 thrusts, indicated at 56, will still be made in the same position as the slit thrusts 54 of the wider bight stitch but the depth thrusts will be made at points indicated at 57 which are nearer the buttonhole slit than the depth thrusts 55 for 15 the wide bight stitch. In other words, the adjustment of the link 37 in the slot 36 for changing the bight of the stitch does not produce any change in the position of the slit thrusts of the needle and the change in the bight occurs at one 20 end only of the stitch, that is, the depth thrust end.

The means herein shown for adjusting the position of the needle to vary the position of the slit thrusts thereof relative to the buttonhole slit 25 comprises an adjustable connection between the rocker 31 and the arm 30 by means of which the relation between the two arms 30 and 32 may be varied.

The rocker member 31 is provided with the 30 two cylindrical bearing portions 42, 43 which find bearing in the two sides of the frame 8. The bearing portion 43 extends beyond the frame and the arm 30 is provided with a split hub portion 44 which encircles the projecting bearing portion 43. The split portion of the hub 44 is provided 35 with a clamping screw 45 by which the hub may be firmly clamped to the bearing portion 43. The bearing portion 43 is provided with a projection 46 through which is threaded an adjusting screw 47 which is confined between and the ends of which bear against two lugs 48 carried by the arm 30. This screw is provided with a flat sided head portion 49 by which it may be turned and with a lock nut 50 for locking it in any adjusted position. The turning of the adjusting screw 47 will serve to turn the rocker member in the arm 30 thereby shifting the position of the arm 32 up or down with relation to the arm 30. Such up or down adjusting movement of the arm 32 with relation to the arm 30 will shift the sleeve 16 up or down correspondingly and thereby shift the needle laterally. This adjustment, however, does not produce any change in the amplitude of jogging 50 movement of the needle but merely shifts the position of the needle bodily thereby shifting the center line of the stitches. This is illustrated in Figs. 5 and 6. Assuming that the machine is adjusted to sew a buttonhole with wide bight 55 stitches indicated in full lines Fig. 5 with the slit thrusts of the needle in the line of the buttonhole slit then by properly adjusting the screw 47 the position of the needle may be shifted so that the slit thrusts will be as indicated at 54 in Fig. 6 wherein they are located at one side of the buttonhole slit but this adjustment does not change the amplitude of jogging movement of the needle and, therefore, the machine will continue to sew the wide bight stitch as shown in full lines Fig. 6.

70 I claim.

1. In a buttonhole sewing machine, the combination with a needle bar and a needle carried thereby, of needle-reciprocating mechanism, a sleeve through which the needle bar reciprocates, a rocker member connected to the sleeve for re-

ciprocating it vertically as said rocker member oscillates, said rocker member having an arm, means to give the sleeve a lateral shifting movement as it reciprocates, cam-actuated means connected to said arm for oscillating the rocker member, and means for adjusting the relative angular positions of said arm and the connection of the rocker member to the sleeve. 5

2. In a buttonhole sewing machine, the combination with a needle bar and a needle carried thereby, of needle-reciprocating mechanism, a sleeve through which the needle bar reciprocates, a rocker having two arms, one of which is connected to said sleeve, means connected to the other arm to oscillate the rocker, and means to 10 give the sleeve a lateral shifting movement as it reciprocates, the arms of the rocker being relatively adjustable to vary their relative angular arrangement. 15

3. In a buttonhole sewing machine, the combination with a needle bar and a needle carried thereby, of needle-reciprocating mechanism, a sleeve through which the needle bar reciprocates, a rocker member having two arms, one of which is connected to the sleeve, a cam-actuated lever 20 having a fixed amplitude of oscillation, a fixed length link pivotally connected at one end to said lever and at the other end to the other arm of the rocker member, the rocking movement of the rocker member shifting the sleeve vertically, 25 means to give the sleeve a lateral shifting movement as it moves vertically thereby to cause the needle to make slit thrusts and depth thrusts, the arm of the rocker member to which the link is attached having a slot formed on the arc of a 30 circle struck from the pivotal connection between said lever and link, said link being adjustable in said slot, means to clamp the link to said other arm in any adjusted position and means other than the link to vary the positions 35 of the slit thrusts with relation to the slit of the buttonhole. 40

4. In a buttonhole sewing machine, the combination with a needle, of needle-reciprocating mechanism, needle-jogging mechanism by which the needle is caused to make alternate slit thrusts and depth thrusts, said needle-jogging mechanism including a rocker member having two arms and means to vary the relative angular position of said arms, whereby the position of the 45 depth thrusts and slit thrusts may be changed while maintaining a given amplitude of jogging movement. 50

5. In a buttonhole sewing machine, the combination with a needle, of needle-reciprocating mechanism, needle-jogging mechanism by which the needle is caused to make alternate slit thrusts and depth thrusts, said needle-jogging mechanism including a rocker member having two arms adjustable relative to each other to vary the 55 angular relation thereof, whereby the position of the slit thrusts and depth thrusts may be changed while maintaining a given amplitude of jogging movement. 60

6. In a buttonhole sewing machine, the combination with a needle bar and a needle carried thereby, of needle-reciprocating mechanism, a sleeve through which the needle bar reciprocates, a rocker member having two arms, one of which is connected to the sleeve, a cam-actuated lever 65 having a fixed amplitude of oscillation, a fixed-length link connecting said lever to the other arm of the rocker member, and means for adjusting the arms of the rocker member angularly 70 with respect to each other. 75

7. In a buttonhole sewing machine, the combination with a needle bar and a needle carried thereby, of needle-reciprocating mechanism, a rocker member, a cam-actuated lever having a fixed amplitude of oscillation, a fixed-length link connecting said lever to said rocker member and by which the rocker member is given a rocking movement, a connection between the rocker member and the needle bar by which rocking movement of the rocker member shifts the needle bar laterally thereby producing slit thrusts and depth thrusts, and means other than either the fixed-length link or the connection between the rocker and the needle bar to vary the position of the slit thrusts relative to the slit of the buttonhole.
8. In a buttonhole sewing machine, the combination with a needle bar and a needle carried thereby, of needle-reciprocating mechanism, needle-jogging mechanism including a rocker member, a cam-actuated lever having a fixed amplitude of oscillation, a fixed-length link connecting said lever to the rocker member and connections between said rocker member and said needle bar to cause the needle bar to have a lateral jogging movement as the rocker oscillates thereby to form slit thrusts and depth thrusts, and means other than either the fixed-length link or the connection between the rocker and the needle bar to vary the position of the slit thrusts relative to the buttonhole slit without changing the amplitude of jogging movement of the needle.
9. In a buttonhole sewing machine, the combination with a needle bar and a needle carried thereby, of needle-reciprocating mechanism, needle-jogging mechanism including a rocker member, a cam-actuated lever having a fixed amplitude of oscillation, a fixed-length link connecting said lever to the rocker member and connections between said rocker member and said needle bar to cause the needle bar to have a lateral jogging movement as the rocker oscillates thereby to form slit thrusts and depth thrusts, and manually-operable means separate from either the fixed-length link or the connection between the rocker and the needle bar to vary the position of the slit thrusts relative to the buttonhole slit without changing the amplitude of jogging movement of the needle.
10. In a buttonhole sewing machine, the combination with a needle, of needle-reciprocating mechanism, needle-jogging mechanism by which the needle is caused to make alternate slit thrusts and depth thrusts, means to vary the amplitude of the jogging movement of the needle by either increasing or decreasing said amplitude on the depth thrust side only of said movement.
11. In a buttonhole sewing machine, the combination with a needle, of needle-reciprocating mechanism, needle-jogging mechanism by which the needle is caused to make alternate slit thrusts and depth thrusts, means to vary the amplitude of the jogging movement of the needle by either increasing or decreasing said amplitude at one end only of said jogging movement, and a separate means to adjust the spacing of the slit thrusts on one side of the buttonhole from those on the other side thereof.
12. In a buttonhole sewing machine, the combination with a needle, of needle-reciprocating mechanism, needle-jogging mechanism by which the needle is caused to make alternate slit thrusts and depth thrusts, a single adjusting means independent of any elements that control the amplitude of jogging movement of the needle and operative to increase or decrease to the same extent the space between the buttonhole slit and the slit thrusts on each side of the buttonhole.
13. In a buttonhole sewing machine, the combination with a needle, of needle-reciprocating mechanism, needle-jogging mechanism by which the needle is caused to make slit thrusts and depth thrusts alternately, and a single adjusting means operative to increase or decrease to the same extent and without affecting the amplitude of the jogging movement of the needle, the space between the buttonhole slit and the slit thrusts on each side of the buttonhole.
14. A buttonhole sewing machine having work-holding means, a needle, needle-reciprocating mechanism, needle-jogging mechanism, having means to control the amplitude of jogging movement and by which the needle is caused to make alternate slit thrusts and depth thrusts, means for giving a relative feeding movement between the work-holding means and the needle, whereby the needle makes slit thrusts and depth thrusts on first one side and then the other of the buttonhole, and means independent of the elements which control the amplitude of jogging movement of the needle to vary the space between the slit thrusts on opposite sides of the buttonhole.

FRANKLIN A. REECE.
